INVENTOR:

James H. Lancaster.

UNITED STATES PATENT OFFICE.

JAMES H. LANCASTER, OF NEW YORK, N. Y.

DESIGN FOR A CYCLE-LAMP.

SPECIFICATION forming part of Design No. 32,202, dated February 6, 1900.

Application filed December 1, 1899. Serial No. 738,931. Term of patent 7 years.

To all whom it may concern:

Be it known that I, JAMES H. LANCASTER, a citizen of the United States, residing at New York, in the county and State of New York, have invented and produced a new and original Design for Cycle-Lamps, of which the following is a specification, reference being had to the accompanying drawings, forming part thereof.

10 Figure 1 is a front view of a cycle-lamp, showing my design. Fig. 2 is a side view of same. Fig. 3 is a rear view of same.

As shown in the drawings, the leading or material features of my design consist in the body of the lamp C in the form of an upright cylinder, having a cup-shaped threaded base portion connected by means of the slanting neck portion D to the upper part of the lamp, comprising the flaring combustion-chamber A 15 and the round disk-shaped water-compartment B, said compartment B being placed in rear of the combustion-chamber, as shown.

The body C is cylindrical in form, terminating at its lower end in a cup-shaped device 25 E, having annular beads e. Around the upper or head portion c' of the body are a plurality of beads or corrugations of successively-decreasing size, arranged on an incline, as shown. Besides this there is an encircling 30 band c².

The water-supply chamber B is in the shape of a round flat disk placed vertically up against the back of the combustion-chamber and is formed with an encircling central bead 35 b' and on each side of same with sloping configurative curves b². Between the flame-chamber and water-supply compartment is a circular collar b⁴, having perforations, as shown. The filling-cap b⁸ of the water-supply cham-

ber is milled around the edge. Besides this 40 there is a star b⁵ on the back of the water-supply chamber.

The combustion or flame chamber A is of cylindrical form and provided with a flaring outer edge a' and a chimney a². The surface 45 of the cylindrical portion is pierced with small apertures on the sides of the jewel a⁴. The chimney a² has an upwardly and outwardly flaring neck a³, provided with a plurality of perforations, as shown, and in the top of this 50 flaring neck is inserted a cover a⁶, formed with a milled edge and sloping upward to a concavo-convex cover-plate a⁵, all perforated by apertures, as shown.

The flame-chamber and the water-supply 55 chamber are both connected to the body of the lamp by a suitable neck portion D. This neck portion is formed with gradually-sloping sides, from which extends a cylindrical portion d', from which protrudes the finger-piece 60 d², having a star d³ on its face. Besides this there are seen suitable pipe connections connecting the different compartments, as at f', f², and f³, and also a dial f⁴ and an indicator f⁶ on the finger-piece d².

Having thus described my invention, what I claim as new, and desire to secure by Letters Patent, is—

The design for a cycle-lamp, substantially as shown and described.

In testimony whereof I have signed my name to this specification in the presence of two subscribing witnesses.

JAMES H. LANCASTER.
